(Cl. D33—14)

To all whom it may concern:

Be it known that I, Robert M. Bennett, a citizen of the United States, residing at Downers Grove, in the county of Du Page and State of Illinois, have invented a new, original, and ornamental Design for a Drafting Table Base, of which the following is a specification, reference being had to the accompanying drawing, forming a part thereof, wherein

Fig. 1 is a perspective view, looking at the rear of a drafting table base, showing my new design, and

Fig. 2 is a perspective view of the same, looking at the front thereof.

The dotted line showing of a drafting table is for illustrative purposes only.

What is claimed is:

The ornamental design for a drafting table base, as shown and described.

ROBERT M. BENNETT.
